ATTORNEY.

UNITED STATES PATENT OFFICE.

ANDERS G. HOEGREN, OF CHICAGO, ILLINOIS, ASSIGNOR TO DAVIS GLOVE COMPANY, OF CHICAGO, ILLINOIS, A CORPORATION.

FASTENER.

No. 891,067.

Specification of Letters Patent.

Patented June 16, 1908.

Application filed December 2, 1907. Serial No. 404,655.

To all whom it may concern:

Be it known that I, ANDERS G. HOEGREN, a citizen of the United States, residing at Chicago, in the county of Cook and State of Illinois, have invented a new and useful 5 Fastener, of which the following is a specification.

My invention relates to fasteners, and especially to that class or type thereof which 10 may be employed in fastening or securing gloves, packages, bundles, overshoes or parcels, etc. firmly and securely in position.

The main object of the invention is to provide a device of the character described 15 which is simple in construction, economic of manufacture, durable, attractive in appearance, which may be readily and quickly manipulated, which will not catch on the garments, and which will effectually accomplish the objects for which it is purposed. When applied on a glove provided with an enlarged gore, the latter portion will without effort be drawn within the wristband; when on a mitten or on a glove not having an enlarged gore, a fold will be created which will not be in the least uncomfortable to the wearer; when on a glove or mitten provided with a slit in the wrist portion, the confronting edges will be drawn neatly and snugly 25 together; and when on an overshoe, as an "arctic" style, any degree of snugness or closeness of fit may be attained, and no buckle or objectionable feature will project to catch and injure the garments of the wearer.

Its utility for carrying school-books will be evident, as will also its adaptability for use 30 by mail carriers on the several individual or separate bundles carried by them, inasmuch as the attachment of the device is instantaneous and detachment as readily effected. It has been used with excellent results by 35 athletes as a wrist-strengthening or binding strap, or rather as a means of securing such strap, any required adjustment being readily produced by the free hand only.

The novel means employed in carrying out the objects of the invention are herein-after described and made the subject matter of the claims hereto appended.

50 The preferred construction of parts and arrangement thereof are illustrated in the accompanying drawings, in which:

Figure 1 is a perspective, showing my improvement in position on a portion of a 55 glove provided with a gore, the parts being

shown in position for wear; Fig. 2, another perspective, taken from a different point of view, and the parts shown in loose positions; Fig. 3, a sectional view, taken in the line $y-y$ in Fig. 1; Fig. 4, a top-plan of the securing plate; Fig. 5, a sectional elevation thereof, in line $x-x$, Fig. 4; Fig. 6, an end elevation of the plate, seen from the rear or pronged end; Fig. 7, an enlarged sectional view, a modification showing a mode of applying the fastener to a strap for carrying a package; and Fig. 8, a view similar to Fig. 5, but showing a tape in place, no tab being employed.

In the several figures of the drawing, like numerals refer to like parts.

1, Fig. 1, indicates the wrist portion, 2 the gore, 3 the back and 4 the stitching on the back of a leather glove of a common and well known construction. Fixed by stitches 5 or 10 in any other suitable manner to one of the confronting wrist-portions is a tab or tag 6 adapted to overlie the gore when in closed position and provided with an aperture 25. The securing plate, in which rests the gist of 15 my invention, is best shown at Figs. 4, 5 and 6 and comprises a base portion consisting of longitudinally disposed side-bars 7, angularly disposed longitudinal continuations 9, a cross-bar 11 at the point of juncture of said 20 bars 7 and 9, it lying in the same plane as do the first recited bars, a transverse end portion 10 uniting the outer ends of the bars 9, it being parallel with but in a lower plane 25 than the bars 7, and a transverse rear end portion 14 lying in the plane of the base, it being provided with tangs 13 or other suitable 30 means whereby the plate may be secured to the tag 6. It will be evident that thus constructed a transverse slot 8, the direction of 35 opening of which is downward through the base members, and a slot 12, the direction of 40 opening of which is substantially longitudinally thereof and at an angle of about 30 degrees thereto is formed, the purposes and 45 advantages of which slots will presently be 50 related. It will be manifest that the several 55 members are integral and that the plate may be formed by a die from a flat strip or sheet 60 of metal, and at a single operation. It will 65 be further evident that the member 10 lies 70 in a plane about the thickness of the tape 75 hereinafter described below that of the base, and that its inner edge constitutes a point for 80 frictional contact when the device is in closed 85 position. The tabs 13 are provided with 90 apertures 15, through which the tape may be 95 passed and secured to the base members. The 100 base members are provided with a series of 105 slots 12, the direction of opening of which is 110 substantially longitudinally of the base members, and the 115 inner edges of which constitute points for frictional contact when the device is in closed position.

position on a glove or other object. The plate is secured in the manner shown best at Fig. 8, by passing the tangs through the body of the tag and clenching the ends, the 5 slots in the plate overlying or registering with the above mentioned opening in the tag.

The tag having been attached to the portion 15 of the wristband 1, the end 16 of a gathering strap 17 is fixed by a staple 18 or 10 otherwise to the other portion, 19, of said band, its free end, 21, threaded through the opening in the tag and through the slot 8, thence over the parting-bar 11, thence 15 downwardly through the slot 12, the side-walls of which are, as before stated, inclined, (preferably at an angle of about 30 degrees,) thence through the tag and thence outwardly beneath the tag-end 20 and the depressed member 10 of the plate. Any preferred means 22 whereby accidental withdrawal of the strap is prevented is fixed on the end thereof. The parts being thus 20 approximately in the position shown at Figs. 2 and 3, the wearer will grasp the free end of 25 the strap and draw thereon until the parts assume the closed position shown at Fig. 1, from which position pressure from the inside, as flexing or bending the wrist joint, will not disturb or release them. Such release, however, 30 may be instantly effected when it is desirable or necessary, by grasping the free end of the tag and either raising it or turning it back upon itself and toward its rear end, whereby the fore end of the plate will be 35 raised and the parts assume the positions shown at Figs. 2 and 3. The frictional contact of the strap 17 against the under side of the tag (caused by the depressed member 10) and like contact of said strap over the parting bar 11 is done away with, the strap running freely through the slots 8 and 12.

When my improvements are used as a luggage or package carrier, an elongated tape is employed. The end 16 thereof is passed

through the opening in the tag, through the slot 8, around the bar 14 and secured to the tab or tag by a staple 23. The end 21 is then passed upwardly through the same slot, thence over the bar 11, downwardly through the slot 12, from whence it is extended to 45 form a convenient means for grasping. I prefer that the member by which the parts are drawn together be a tape, for two reasons: first, because it may be always uniform in thickness; and second, because it will not 50 be easily affected by moisture. Other means than tangs 13 may be employed for attachment of the plate to the tag if preferred. Indeed, both the tangs and the tag may be dispensed with in one form in which the device 55 may be used.

Having thus set forth the construction and operation, the purposes and advantages of my invention, I claim as new and desire to secure by Letters Patent the following, 60 namely:

1. A fastener comprising a tab having an opening, a plate fixed to and overlying the tab and provided with openings registering with the one in the tab, said plate including 70 parallel members lying in different planes and angularly disposed members by which they are connected.

2. The combination with an apertured tab and the wristband of a glove to which it is 75 secured, of a gathering-strap secured to said wristband, and a fastening plate fixed to said tab and provided with transverse slots for the reception of said tape, the walls at the ends of one of said slots being inclined with 80 relation to the other walls thereof.

In testimony whereof I have hereunto affixed my hand this 20 day of November, 1907.

ANDERS G. HOEGREN.
